UNITED STATES PATENT OFFICE.

JOHN W. WILLIAMS, OF NORTH BIRMINGHAM, ALABAMA.

GAGE.

1,090,003.

Specification of Letters Patent. Patented Mar. 10, 1914.

Application filed March 7, 1913. Serial No. 752,777.

To all whom it may concern:

Be it known that I, JOHN W. WILLIAMS, a citizen of the United States, residing at North Birmingham, in the county of Birmingham and State of Alabama, have invented new and useful Improvements in Gages, of which the following is a specification.

This invention relates to gages, and its object is to provide a device which is especially adapted for use as an attachment for or in conjunction with a combination square and rule, to serve as a surface gage, depth and scratch gage and caliper gage, at will.

A further object of the invention is to provide a device of this character which can be conveniently applied and removed, and which is adapted to hold the scribe at any required angle.

The invention consists of the features of construction, combination and arrangement of parts hereinafter fully described and claimed, reference being had to the accompanying drawings, in which:—

Figure 1 is a front view of a combination square and rule, showing the device arranged for use as a surface gage. Fig. 2 is a back view of the blade of the tool, showing the device arranged for use as a depth and scratch gage. Fig. 3 is a similar view, showing the device arranged for use as a caliper gage. Figs. 4 and 5 are sectional views on the lines 4—4 and 5—5 of Fig. 1. Fig. 6 is a perspective view of the bracket. Fig. 7 is a view of the parts of the scribe clamp separated and arranged in proper relation. Fig. 8 is a detail view of the cam for clamping the bracket to the tool blade.

Referring to the drawings, 1 designates a combination square and rule, the blade 2 of which is provided on one side with a longitudinally extending groove or slot 3. The gage constituting my invention is adapted to be adjustably mounted upon the blade 2 and comprises a bracket 3' provided at one side with an apertured ear 4 extending outwardly therefrom, the body of said bracket being formed with an opening 5. From the body of the bracket projects a pair of spaced guide plates 6 and 7 designed to overlie the opposite faces of the blade 2. As shown, the plate 6 extends at its outer edge beyond the edge of the plate 7 and is provided with a guide flange 8 to engage the groove or slot 3, whereby the bracket is adapted to be slidably mounted upon the blade.

In order to secure the device in adjusted position along the length of the blade, I provide a clamping member 9 consisting of a stem journaled within the opening 5 and 60 provided with a milled head 10. The opening 5 communicates with the space between the inner ends of the plates 6 and 7, and the stem is formed with a notch or recess 11 adapted when in register with said space to 65 permit adjustment of the bracket along the blade. The stem is so formed as to operate as a cam or eccentric, whereby when it is turned to bring its unnotched surface into engagement with the edge of the blade, the 70 said clamping device will bind against such edge of the blade and throw the flange 8 into engagement with one of the walls of the groove or slot 3 thus clamping the gage firmly and securely in position. 75

Extending through and journaled in the opening in the ear 4 is a pivot pin 12 having at one end a flange or head 13 bearing against one side of said ear, and provided with a diametrically extending opening 14. 80 The opposite end of the pin projects beyond the opposite face of the ear and is threaded to receive a milled clamping nut 15. Between this clamping nut and the ear are interposed washers 16 and 17, the meeting 85 faces of which are provided with recesses 18 registering with the opening 14. The said opening 14 and recesses 18 are adapted for the passage of a scribe 19 having a straight pointed scribing end 20 and a right angularly bent scribing end 21, the construction being such that the scribe may be extended across and at different angles to the blade 2 to perform different functions. It will be understood, of course, that by relaxing the 90 clamping nut 15 the scribe may be turned with and upon the pin 12 as an axis, and that then upon tightening said nut the scribe will be firmly clamped in adjusted position between the curved faces of the washers. 95

In the accompanying drawings I have shown, in Fig. 1, my improved gage applied to the blade 2 for use as a surface gage, while in Fig. 2 I have shown it arranged for use as a depth and scratch gage, and in Fig. 105 3 for use as a caliper gage, for which purposes it is adapted to be efficiently employed, and it will be apparent to those versed in the art that it may be employed for other analogous and useful purposes. It will be 110 seen that it provides a gage which can be readily and conveniently attached to and de-

tached from the blade of a combination square and rule or other similar tool, and that it permits of the longitudinal adjustment of the scribe, as well as the arrangement of the scribe at varying angles to the blade, as occasion may demand.

I claim:—

1. The combination with a blade having a groove therein, of a gage of the character described comprising a bracket having a pair of guide plates, one of greater length than the other and provided at its outer edge with a clamping rib to engage said groove, said bracket having an opening communicating with the space between the plates and an outwardly extending ear, a clamping cam journaled in said opening and adapted to engage one of the edges of the blade, a pivot pin journaled in the ear and having an opening therein, a scribe extending through the opening in the pin, and clamping means carried by the pin to engage and hold said pin and scribe in adjusted position.
- 20 2. The combination with a blade having

a groove therein, of a gage of the character described comprising a bracket having a pair of guide plates, one of greater length than the other and provided at its outer edge with a clamping rib to engage said groove, said bracket having an opening communicating with the space between the plates and an outwardly extending ear, a clamping cam journaled in said opening and adapted to engage one of the edges of the blade, a pivot pin journaled in the ear and having an opening therein, a scribe extending through the opening in the pin, and clamping means carried by the pin to engage and hold said pin and scribe in adjusted position.

In testimony whereof I affix my signature in presence of two witnesses.

JOHN W. WILLIAMS.
